SLUMBER SCREEN

Mary Irene Abrams and Gertrude Abrams,
Portland, Oreg.

Application August 21, 1933, Serial No. 686,120

1 Claim. (Cl. 5—330)

Our invention relates to a device which is particularly adapted to screen the face of a sleeping person. Said device may be arranged between two people sleeping in the same bed, or may be arranged at the side of a person to protect him against rays of light and draft, or may be arranged to secure a measure of privacy such, for example, as in a hospital.

A device of this character is adapted to be incorporated in a removable attachment adapted to be arranged at the head of a bed and provided with a flat, elongated base adapted to underlie the mattress, a standard extending upwardly about one end of the mattress, and a screen or shield overlying the bed and extending longitudinally thereof. Said device may also be incorporated in a screen provided with a clamping device adapted to secure said screen to the head of a bed, or may be incorporated in a device which is fixed to but adjustable upon the head of said bed and thus be more or less permanently incorporated in said bed.

A supplementary object of our invention is to provide a device of this character which incorporates pockets upon one or both faces of said screen, said pockets serving as convenient storage compartments for small articles or packages which may be deemed a convenience, or which may serve as compartments for small valuables of whose safety one may be concerned.

Further details of our invention, the objects thereof and details of construction are herein-after illustrated with reference to the accompanying drawing, in which:

Fig. 1 is a plan view of a slumber screen constituting an attachment to a bed, but to be readily removable therefrom;

Fig. 2 is a fragmentary elevation thereof with a portion of the base shown broken away to disclose a detail of construction;

Fig. 3 is a modification of our invention showing a fragment of a slumber screen secured to a portion of a bed or other standard or support by means of a clamp;

Fig. 4 is a still further modification of our invention illustrating how a standard or other support can be secured to the head of a bed in a more or less permanent manner and yet permit the removal and adjustment of the screen portion thereof; and

Fig. 5 is a perspective view of a bed showing the first embodiment of our invention in place thereon, said figure illustrating how said device is arranged to overlie the sleeping surface of the bed and with a base arranged below the mattress.

In the embodiment of our invention shown in Figs. 1, 2 and 5, said device is provided with a flat, elongated, tongue-shaped base *a*, at one end of which an upstanding mounting *a'* is arranged. A standard *b* in the form of a round rod is screw-threaded in the mounting *a'*. The screw threads permit the ready removal of said standard from the mounting, but if it is not deemed necessary to effect said removal, the standard and the base can be made of one element.

The shield *c* is secured to the standard by an element *d*, which encircles the standard and is secured to the shield by wing nuts *e*. The provision of wing nuts for securing the shield to its element *d* permits said shield to be easily and quickly removed from said element and thus from the standard *b*. Said shield is preferably covered with some decorative fabric or is decorative-ly ornamented and one or more pockets *c'* are arranged upon the face or faces of said shield to provide a convenient storage space for small articles such, for example, as a handkerchief, watch, or other article which the sleeper wishes to have convenient.

Adjustment of said shield upon the standard is accomplished by securing said parts together by a set screw *f*. By slackening the set screw *f*, said shield is permitted to rotate about its standard and is also permitted to shift longitudinally thereof. When the parts are arranged in the desired position, they can be held in said position by seating the end of the set screw against the standard.

As is shown in Fig. 5, this embodiment of our invention is adapted to be arranged at the head of the bed *g* with the standard extending just inside of the head piece *g'* of said bed. The base *a* of our device, shown in dotted outline, underlies the mattress of said bed, while the shield portion extends above and overlies the sleeping surface thereof, which is covered by the spread *g2*. Said slumber screen is arranged in the center of the bed in Fig. 5 and lies between the pillows *g3* and thus defines two sleeping spaces, one at each side of said slumber screen, and provides a measure of privacy between said two sleeping spaces. To serve as a screen for shielding the sleeper's eyes from rays of light such, for example, as from a window or from an electric light, said slumber screen can be shifted to either side of the bed and thus it would lie at the outer edges of said sleeping spaces rather than between them. To serve as a shield of this character, said slumber screen should be imperforate and opaque. The provision of the mounting element *d* and

the wing nuts *e* permit the ready removal of a shield *c* and thus different shields can be provided, some having a factor of transparency, if this is desirable, and others having different decorative effects or finishes.

In Fig. 3 we show a fragment of a slumber screen adapted to be secured to a standard *h* by means of an adjustable clamp *i*. This permits a shield *c* with its elements *d* to be removably secured to a fixed portion of a bed or similar device, which is provided with elements conveniently gripped by a clamp of this character.

In Fig. 4 a slumber screen embodying our invention is shown incorporated as a fixed part of the head piece *j* of a bed. A vertical slot is defined between two spaced cleats *k* carried by said head piece. Said cleats may be formed of harmonizing or contrasting finishes with respect to the head piece of said bed and may be formed, for example, of carved wood and will thus form a decorative design upon the head of said bed. Lying within the slot *l* formed by said cleats is a vertically-arranged standard *m* pivotally and removably secured between two fittings *n* and *n'*. The fitting *n'* includes a pivotal cup *n2*, into which the lower end of the standard *m* is screw-threaded. The fitting *n* defines a loose-fitting eye *n3*, thru which the standard *m* is slidably mounted and which provides sufficient clearance to permit the removal of said standard from said fittings.

To mount said standard in place, it is passed thru the eye portion of the fitting *n* and secured

by its threaded end *m'* into the cup *n2*. Tight-fitting but slideable rings *o* are arranged upon said standard and are adapted to be secured at each side of the mounting element *d* for the shield *c* to prevent longitudinal movement of said shield upon its standard. Said rings also may be seated tightly against said mounting element to prevent the rotation of said shield upon said standard.

In each of the modifications the same type of shield is adapted to be used. Said shield can be made of wood, metal, composition, or any appropriate material. Because of its strength and relative lightness, we have found that plywood serves as an excellent material but, of course, we do not wish our invention limited to the use of said material.

We claim:

A slumber screen including a flat, elongated, tongue-shaped base provided with an upwardly arranged portion at one end thereof extending laterally of said base, a standard secured to said upwardly arranged portion, a relatively stiff shield extending laterally from said standard, said shield being vertically arranged with one edge adjacent said standard, a U-shaped member extending about the full length and stiffening that edge of the shield adjacent the standard, and quick detachable means associated with said U-shaped member securing the latter to said standard and to said shield.

MARY IRENE ABRAMS.
GERTRUDE ABRAMS.
